MULTIPURPOSE FLOOR TREATING
MACHINE

William Portnow, New York, N. Y.

Application June 27, 1950, Serial No. 170,536

9 Claims. (Cl. 51—176)

1

The present invention relates to new and useful improvements in a floor treating machine and, more particularly, to a single machine which can be used as a floor sander or wlexer or as a vacuum cleaner.

The present application is a continuation-in-part of my previous application Serial No. 55,853, filed October 22, 1948, now abandoned.

More specifically, the machine of the present invention is constructed to be light in weight to be easily transported from place to place by one man and to have a hollow body within which there is mounted a rotatable drum with means for mounting a sheet of abrasive material in position thereabout without the necessity of removing the drum from the body in a manner so that the machine can be used as a floor sander.

Another object of the present invention proposes a novel means for removably mounting the drum in position so that it can be removed therefrom without the use of any tools to have a polishing sleeve or the like engaged thereon so that the machine can be used as a floor wlexer.

Still another object of the present invention proposes mounting a dust pan within the hollow body to the rear of the rotatable drum and which is connected by a tube to a vacuum box in a manner so that dust set up by the drum when used for floor sanding will be collected by the dust pan and sucked into the vacuum box through the tube.

A further object proposes the provision of a fan for creating a vacuum within the vacuum box for drawing the dust into that vacuum box and then to discharge the dust into a suitable dust collecting bag mounted on the machine.

Still further, the present invention proposes constructing the machine so that the rotatable drum can be completely removed from the machine to expose the front end of the tube which connects the dust pan with the vacuum box in a manner so that the end of a conventional vacuum cleaner hose can be connected with that tube adapting the machine to be used as a vacuum cleaner.

It is a further object of the present invention to construct a floor treating machine which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

2

In the accompanying drawings forming a material part of this disclosure:

Fig. 1 is a side elevational view of the floor treating machine constructed in accordance with the present invention.

Fig. 2 is an enlarged plan view of the main portion of the machine of the present invention.

Fig. 3 is a longitudinal sectional view taken on the line 3—3 of Fig. 2.

Fig. 4 is an enlarged detailed view of a portion of Fig. 3.

Fig. 5 is a transverse vertical sectional view taken on the line 5—5 of Fig. 2.

Fig. 6 is a transverse vertical sectional view taken on the line 6—6 of Fig. 2.

Fig. 7 is a partial longitudinal sectional view taken substantially on the line 7—7 of Fig. 6.

Fig. 8 is a partial transverse vertical sectional view taken substantially on the line 8—8 of Fig. 3.

Fig. 9 is an enlarged detailed view of a portion of Fig. 1.

Fig. 10 is an enlarged partial horizontal sectional view taken on the line 10—10 of Fig. 9.

Fig. 11 is an enlarged partial horizontal sectional view taken on the line 11—11 of Fig. 9.

Fig. 12 is an enlarged partial vertical sectional view taken on the line 12—12 of Fig. 11.

Fig. 13 is an enlarged partial plan view looking in the direction of the line 13—13 of Fig. 1.

Fig. 14 is an enlarged sectional view taken on the line 14—14 of Fig. 13.

Fig. 15 is a perspective view of the rotatable drum removed from the machine and with a polishing sleeve engaged in position thereon.

The floor treating machine, according to the present invention, includes a hollow body 20 molded of any suitable metal and of substantially channel-shape to have a top wall 21, depending side walls 22 and 23, a front wall 24, a rear wall 25 and an open bottom. Positioned on the front wall 24 there is a bumper 26. The bumper 26 is formed of rubber and slipped upward into position onto the bottom edge of the front wall 24 and is secured in position by several spaced rivets 27, one of which is shown in Fig. 3.

Rotatively positioned within the body 20, adjacent the front end thereof, there is a drum 28 formed of any suitable light but hard wood. The drum 28 is, of course, circular in cross-section and has its ends recessed. Within the recessed ends of the drum 28 there is concentrically mounted metallic plates 29, see Figs. 5 and 15, which are secured in position by the usual wood screws 30. Projecting concentrically from the plates 29 there are bearing bosses 31 formed with square holes 32. A sheet of abrasive material 33 (sandpaper or

the like) is to be wrapped about the drum 28, as shown in Figs. 1, 3, 5 and 9.

Novel means is provided for securing the abrasive material 33 in position about the drum 28. To accomplish this, the drum 28 is formed along one side thereof with a longitudinal slot 34 into which the ends of the sheet of abrasive material 33 are engaged, see Figs. 3 and 9. Slipped into position within the slot 34, between the adjacent faces of the inturned ends of the sheet of abrasive material 33, there is a metal bar 35. The faces of the metal bar 35 are roughened, see Fig. 5, much the same as a file or rasp so as to have a grip on the surface of the sheet of abrasive material 33. Projecting longitudinally from the ends of the metal bar 35 and within the recessed ends of the drum 28, there are threaded studs 36, see Figs. 5 and 9, and upon which wing nuts 37 are threaded. The wing nuts 37 are arranged to be tightened against the ends of the drum 28 within the recessed ends thereof so as to securely tighten the metal bar in position and retain the sheet of abrasive material 33 in position about the drum 28.

With the sheet of abrasive material 33 in position about the drum 28, the machine is ready to be used as a conventional sander for scraping and smoothing the surface of a floor. However, with the sheet of abrasive material 33 and its holding parts completely removed from the drum 28, a polishing sleeve 38, see Fig. 15, can be slipped into position on the drum adapting the machine for use as a floor wazer. The polishing sleeve 38 is preferably formed of a durable cloth material and of a diameter to fit snugly and frictionally grip the surfaces of the drum and so frictionally retain its position thereon.

Means is provided for removably and rotatively mounting the drum 28 in position between the side walls 22 and 23. That mounting means comprises a trunnion 39 which is rotatively mounted through the side wall 23, see Fig. 5, and which is provided at its inner end with a square end portion 39^a to be received within the square hole 32 of the adjacent plate 29 of the drum. The side wall 22, at the other end of the drum 28, is formed with a separate wall portion 40 through which a second trunnion 41 is rotatively mounted in end alignment with the first trunnion 39. The trunnion 41, at its inner end, is formed with a square end portion 41^a, again see Fig. 5, received within the square hole 32 of the adjacent plate 29. Thus, when the trunnions 39 and 41 are rotated the drum 28 will be rotated.

The wall portion 40 is set into a suitable opening cut in the side wall 22 and means is provided for retaining the wall portion in position in which the square end portion 41^a of the trunnion 41 will be retained in engagement with its respective bearing boss 31. Extending laterally from the wall portion 40, adjacent the top edge thereof, there are pins 42 and 43 received in suitable holes 44 formed in the side wall 22 to pivotally retain the wall portion 40 in position. The pin 43, see particularly Fig. 10, is slidably received with a suitable hole 45 formed in the adjacent edge of the wall portion 40. An expansion spring 46 is positioned within the hole 45 behind the pin 43 and urges the pin into an extended position in which its outer end will be engaged with the respective hole 44 of the side wall 22. A detent 47 projects radially from the pin 43 and passes through an elongated slot 48 formed in the inner face of the wall portion 40. When the wall por-

tion 40 is pivoted to an open position, the detent 47 can be used for urging the pin 43 against the action of the spring 46 to disengage its outer end from the respective hole 44 so as to free the wall portion 40 for complete removal, if desired.

The side edges of the side wall 22 adjacent the bottom of the wall portion 40 are formed with inwardly projected ledges 49, see Figs. 9, 11 and 12, arranged to be received within complementary cutouts formed in the back face of the wall portion 40. The ledges 49 act to limit inward pivoting of the wall portion 40.

Catches are provided along the bottom edge of the wall portion 40 for retaining the wall portion against outward pivoting. The catches are characterized by elongated metal pieces 50 slidably positioned in spaced end alignment within a groove 51 formed in the wall portion 40 and which opens to the front face thereof. The open front of the groove 51 is closed by means of a metal plate 52 which is welded, brazed or in any other manner secured in position. Positioned within the groove 51 between the adjacent inner ends of the metal pieces 50, there is an expansion spring 53 which extends the metal pieces 50 to engage their beveled outer ends 54 into complementary keeper recesses 55, see Fig. 11, formed in the adjacent edges of the side wall 22. The outer ends 54 of the metal pieces 50 are beveled in a direction to slip past the edges of the side wall 22 as the wall portion 40 is pivoted from an opened to a closed position.

The inner ends of the metal pieces 50 are provided with right angularly extended finger pieces 56 which are projected through elongated slots 57 formed in the metal plate 52. The finger pieces 56 provide a grip by which the metal pieces 50 can be drawn inward against the action of the spring 53 so as to disengage their beveled outer ends 54 from the complementary keeper recesses 55 to free the wall portion 40 to be pivoted to an open position about the pins 42 and 43. In that open position of the wall 40, the square inner end portion 41^a of the trunnion 41 will be withdrawn from the square hole 32 of the respective bearing boss 31 freeing the drum 28 to be completely removed from the machine.

A source of power in the form of an electric motor 58 is mounted on top of the body 20 directly over the drum 28 and with the drive shaft 57 positioned parallel to the axis of the drum. A transmission means is interposed between the drive shaft 57 of the motor 58 and the trunnions 39 and 41 for rotating the trunnions and in turn rotating the drum 28. That transmission comprises bevel gears 59 secured to the outer portions of the trunnions 39 and 41 adjacent the outer faces of the side wall 23 and the wall portion 40. The bevel gears 59 are enclosed within suitable housings 60 secured to the outer faces of the side wall 23 and the wall portion 40 by means of screws 61. Within the housings 60, there are bevel gears 62 which mesh with the bevel gears 59, as shown in Fig. 5. The bevel gears 62 are formed with stud shafts 63 which are rotatively extended through the top walls of the housings 60 and secured to the bottom ends of vertically extended flexible shafts 64.

The outer ends of the drive shaft 57 have secured thereto bevel gears 64 which are enclosed within housings 65 secured to the ends of the casing of the motor 58 by means of screws 66. The bevel gears 64 in turn mesh with bevel gears 67 located within the housings 65. The bevel gears 67 are formed with stud shafts 68 rotatively

extended through the bottom walls of the housings 65 and secured to the top ends of the flexible shafts 63. Thus, when the motor 56 is energized its drive shaft 57 will rotate and in turn rotate the trunnions 39 and 41 and cause the drum 28 to be rotated.

Extended upward and rearward from the body 20, there is a handle 69 formed of a pair of upwardly converged handle members 70, see Figs. 1, 2, 6 and 13. The bottom ends of the handle members 70 are flattened and secured to the side walls 22 and 23 by rivets 71. Extended across the top ends of the handle members 70 there is a grip member 72 secured in position by rivets 73, see Fig. 13. Positioned between the top ends of the handle members 70 adjacent the grip member 72, there is a box 74 which encloses a switch, not shown, having an operator stem 75 extended from the top of the box by which the switch can be turned on and off. An electric cable 76 extends into the box, see Fig. 13, and is provided at its outer end with a plug 77 of conventional construction for insertion into a conventional electric outlet receptacle. Within the box 74, the cable 76 is connected to the switch and has an end portion 78 extended from the box to be connected to the motor 56 for supplying the required electric current for operating or energizing the motor 56. The manner in which the end portion 78 of the cable 76 is extended to the motor 56 is not shown as such details form no part of the present invention and are generally known by those skilled in the art to which the present invention pertains. The box 74 is supported in position on the handle members 70 by several C-shaped clamps 79 engaged about the handle members 70 and secured to the sides of the box 74 by rivets 80.

The rear portion of the body 20 is supported by a pair of side wheels 81 and a rear wheel 82. The side wheels 81 are positioned adjacent the side walls 22 and 23 and the rear wheel 82 is positioned against the rear wall 25 between the side walls. The side wheels 81 are rotatively positioned on pins 83 extended between the depending side arms of inverted U-shaped brackets 84 extended over the tops of the side wheels 81. The rear wheel 82 is likewise rotatively positioned on a pin 85 extended between the depending side arms of an inverted U-shaped bracket 86 extended over the top of that rear wheel. The inverted U-shaped brackets 84 are fixed to the bottom ends of the vertical bars 87 which are square in cross section. A pin 88 pivotally attaches the U-shaped bracket 86 to the bottom end of a vertical bar 89 which is also square in cross section. A washer 90 is positioned on the pin 88 between the adjacent faces of the bracket 86 and the bar 89 so that the rear wheel 82 is free to pivot in all directions about a vertical axis to function in the nature of a steering wheel for guiding the machine as desired over floor surface.

The bars 87 and 89 are slidably but non-rotatively extended through complementary square holes formed in the superimposed arms of C-shaped brackets 91. The C-shaped brackets 91 are fixedly secured to the inner faces of the side walls 22 and 23 and the rear wall 25 by means of rivets 92, see Fig. 3. Integrally formed with and extended vertically upward from the top ends of the bars 87 and 89, there are threaded stud shafts 93 received within internally threaded tubular screw members 94. The top ends of the screw members are reduced and rotatively extended through complementary holes formed in the top

wall 21 of the body. Knobs 95 are fixed to the top ends of the tubular screw members 94 above the top wall 21 by which those tubular screw members can be turned in one direction or the other. As the tubular screw members 94 are turned in one direction or the other, they will cause the bars 87 and 89 to be raised or lowered, due to the threaded connection of the stud shafts 93 with the tubular screw members 94. That will cause the vertical position of the wheels 81 and 82 to be adjusted to control the pressure of the drum 28 on the floor surface.

Positioned behind the drum 28, there is an arcuate dust pan 96, see particularly Fig. 3. The dust pan 96 is extended the full width of the space between the side walls 22 and 23 and is secured thereto by right angular lugs 97 which extend from the ends of the dust pan 96 along the inner faces of the side walls 22 and 23. The lugs 97 are secured to the side walls by means of rivets 98. The top edge of the dust pan 96 engages the inner face of the top wall 21 and the bottom edge of the dust pan extends well below the bottom edges of the side walls 22 and 23. Thus, the dust pan functions to catch all dust and other dirt which is thrown upward and rearward by the drum 28 during scraping and sanding of the floor surface.

Mounted within the body 20 between the dust pan 96 and the rear wall 25, there is a hollow vacuum box 99. The vacuum box 99 has an open top closed by a wall 100 secured in position by screws 101. The vacuum box 99 is mounted in position by pairs of brackets 102 extended between the dust pan 96 and the front wall of the vacuum box and the rear wall of the vacuum box and the rear wall 25 of the body 20.

A tube 103 connects the dust pan 96 with the vacuum box 99, as shown in detail in Fig. 3. The tube 103 is integrally formed with or welded to the dust pan and has its rear end projected into a complementary hole formed in the front wall of the vacuum box 99. A rubber ring 104 surrounds the rear end of the tube 103 and is positioned between the vacuum box 99 and a flange 105 formed on the tube to seal the point where the tube 103 enters the vacuum box 99. The tube 103 functions as a passageway for the movement of a dust-air mixture from the dust pan 96 into the interior of the vacuum box.

One side of the vacuum box 99 is connected to an exhaust fan assembly 106 and the other side is connected to a diaphragm assembly 107, see particularly Fig. 6. The fan assembly 106 is characterized by a fan housing 108, see Figs. 6 and 7, enclosing a rotor 109 having a plurality of radially projected fan blades 110. Projected laterally outward from the side of the housing 108, there is a tubular projection 111 secured to the inside face of the side wall 22 by rivets 112. A stud shaft 113 is rotatively mounted through the side wall 22 and is provided at its inner end with a square end portion 114 which extends into a complementary concentric square hole 115 in the side of the rotor 109 for causing the rotor to be rotated when the stud shaft 113 is rotated. The means for rotating the stud shaft 113 will hereinafter be described.

Projecting laterally from the other side of the fan housing 108, there is a tubular throat 116 formed with a flange 117 positioned against the outer face of the vacuum box 99 concentric with a discharge opening formed in the side wall of the vacuum box. A piece of coarse metal

screening 118 extends across the discharge opening and is reinforced at its peripheral edges by a metal ring 119. Screws 120 are threadedly passed through the metal ring 119, the edges of the screening 118, the wall of the vacuum box 5 and into the flange 117 securing those parts together as a unit.

The screening 118 is provided to permit the free passage of the dust-air mixture from within the vacuum box 99 into the fan assembly 106 10 and to prevent the free passage of larger articles, such as nails and the like, into the fan assembly 110. with resulting damage to the fan blades 110. Such large articles will drop downward within the vacuum box 99 and collect in a removable 15 drawer 121 positioned in the bottom of the vacuum box 99. One side of the drawer 121, see Fig. 6, is provided with a handle 122 by which the drawer can be removed to be emptied of its contents. The drawer 121 is made of a size to air tightly seal the bottom of the vacuum box 99.

One side of the fan housing 108 is formed with an upwardly extended discharge tube 123 formed at its top end with an outwardly directed flange 124, see Fig. 7. A discharge pipe 125 is mounted through the top wall 21 of the body 20 and is formed with a flange 126 at its bottom end aligned with the flange 124. Positioned between the flanges 124 and 126, there is a rubber sealing ring 127 and the pipe 125 is secured to the tube 123 by a plurality of screws 128 which are passed through the flanges 124 and 126.

Mounted between the handle members 70 below the box 74, there is a dust bag 129, see Figs. 1, 2 and 13. The dust bag 129 is made of rubberized cloth or other air impervious material to insure that no air-dust mixture will be discharged therefrom. At its bottom end, the bag 129 is engaged with several hooks 130 pivotally secured to clamps 131 mounted about the handle members 70, see Figs. 2 and 6. The top end of the bag 129 is engaged with hooks 132, see Fig. 13, mounted on springs 133 in turn supported on lugs 134 which extend from the switch box 74. At its bottom, the dust bag 129 is formed with a tubular extension 135, see Figs. 1, 2 and 7, which has an internally threaded metal collar 136 clamped in position thereon.

The free end of the discharge pipe 125 is enlarged, see Fig. 7, and has the bottom end of a semi-rigid hose 138 extending thereinto. The bottom end of the hose 138 is formed with an outwardly directed flange 139 which abuts the free end of the discharge pipe 125. The exterior of the enlarged free end of the discharge pipe 125 is threaded. The internally threaded metal collar 136 is threaded onto the end of the discharge pipe 125 and against an outwardly directed flange 137 formed on the discharge pipe. Interiorly, the collar 136 is formed with an inwardly directed flange 140 which engages the flange 139 of the hose securely clamping the bottom end of the hose 138 in position within the enlarged end of the discharge pipe 125. When the collar 136 is unthreaded from the end of the discharge pipe 125 the bottom end of the hose 138 can be slipped out of the end of that discharge pipe.

The other end of the hose 138, as shown in Figs. 6 and 7 is projected upward along one side of the dust bag 129 and has its top end stopped short of the top end of the dust bag, as shown in Fig. 13. With this arrangement of the top end of the hose 138, the dust-air mixture discharging from that hose will impinge against the top

end of the dust bag with considerable force causing the mixture to break up releasing the dust to fall down within the bag 129 and collect in the bottom thereof. When the collar 136 is unthreaded from the discharge pipe 125, the hose 138 can be pulled from within the bag 129 leaving the tubular extension 135 of the bag 129 unobstructed so that the dust within the bag can be shaken therefrom through that extension.

In the top corner opposite the corner in which the free end of the hose 138 discharges, the dust bag 129 is formed with an air discharge hole 142, see Figs. 13 and 14, across which there is extended a piece of air pervious but dust impervious cloth filter material 143. The edge portions of the dust bag 129 surrounding the hole 142 and the filter material 143 are overlapped and clamped between metal rings 144 and 145 secured in position by nut and bolt assemblies 146. The nut and bolt assemblies 146 permit the metal rings 144 and 145 to be separated when desired for replacement of a fresh piece of filter material 143 when necessary. The filter material 143 functions to permit the free discharge of air from the dust bag while retaining the dust within the bag.

The end of the tube 103, which connects the dust pan 96 with the interior of the vacuum box 99, see Fig. 3, is formed internally at its front end with threads 147. When the drum 28 is removed from the machine, clearance is provided so that the end of a conventional flexible hose of the type used in hotels, theatres and other commercial institutions, which hose is not shown on the drawings, can be screwed into the end of that tube so that the machine can be used for vacuuming cleaning purposes. Extended upward from the top of the vacuum box 99, there is a length of pipe 148 which is projected upward through the top wall 21 of the body 20 and has its top end normally closed by a cap 149 screw threaded onto the top of the pipe 148. The bottom end of the pipe 148 is formed with a flange 150 which surrounds a hole 151 formed in the top wall 100 of the vacuum box 99. Positioned 40 between the flange 150 and the top wall 100, there is a rubber sealing ring 152 and those parts are secured together by means of rivets 153.

When the cap 149 is removed from the top end 50 of the pipe 148, the usual flexible hose, of smaller diameter than the flexible hose referred to in the paragraph next above and commonly used for vacuum cleaning purposes in the home, can be connected with that top end of the pipe permitting the machine to be used for vacuum cleaning in the home without the necessity of removing the drum 28.

Positioned in the tube 103, there is a valve for 55 closing the tube when the pipe 148 is being used for vacuum cleaning purposes. The valve is comprised of a valve housing 154, see Figs. 3 and 8, formed in the tube 103 intermediate of its ends and which has an open top. Slidably positioned within the valve housing 154 there is a valve 60 plate 155, which has attached to the top end thereof a valve stem 156 formed of flexible metal. The stem 156 is extended freely upward through a tubular member 157 secured to the bottom face of the top wall 21 of the body 20. The stem is 65 then passed through a complementary hole formed in that top wall and is formed with a handle 158 at its top end by which the stem 156 can be raised or lowered to correspondingly raise the valve plate 155 to an inoperative position or to 70 lower the valve plate to an operative position clos- 75

ing off the tube 103. At its top end, see Fig. 4, the tubular member 157 is formed with an inwardly projected lug 159 and the valve stem is formed with spaced complementary notches 160 and 161. When the notch 160 is engaged with the lug 159 as shown on the drawings, the valve stem 156 is retained in a raised position in which the valve plate 155 is in an inoperative position. On the other hand, when the notch 161 is engaged with the lug 159, the valve stem 156 is in a lowered position and the valve plate 155 is also lowered to an operative position.

A leaf spring 162 within the tubular member 157 has one end riveted to the wall of the tubular member opposite the lug 159 and has its other end engaged with the face of the valve stem 156 for holding the stem 156 in a position in which either its notch 160 or its notch 161 is engaged with the lug 159. The flexible material of which the valve stem 156 is formed permits it to be flexed to disengage its notches from the lug 159 to free the valve stem to be either raised or lowered.

The diaphragm assembly 107, previously referred to and as illustrated in Fig. 6, is comprised of a metal housing 163 having an inwardly directed throat portion 164 in turn formed with an outwardly directed flange 165 which surrounds a hole formed in the side wall of the vacuum box 99 on the side opposite the fan assembly 166. Extended across the latter hole there is a piece of dust-impervious filter material 166 permitting the free passage of air but stopping the passage of dust. The edges of the filter material 166 are reinforced by a metal ring 167 through which screws 168 pass to in turn pass through the filter material 166, the wall of the vacuum box 99 and the flange 165 so as to secure those parts together as a unit.

The side of the diaphragm housing 163 opposite the vacuum box 99 is closed by a wall. Within the housing 163 there is a diaphragm comprised of a rubber ring 170 across which a thin sheet of rubber material 171 is stretched. The sheet of rubber material 171 is formed with a small hole 172 (about one-eighth inch in diameter), see Fig. 6.

The diaphragm is positioned between the throat side of the housing 163 and a circular flange 163^a within the housing. The flange 163^a functions to hold the diaphragm spaced from the wall which closes the side of the housing 163 remote from the vacuum box 99. The periphery of the housing 163 between the flange 163^a and the closing wall is formed with a plurality of holes 169 connecting the interior of the housing with the outside atmosphere.

The diaphragm assembly 107 functions to break the initial force of the vacuum within the vacuum box 99 when the fan assembly is started and to maintain a constant vacuum of great force within the vacuum box 99. When the fan is started, the sheet of rubber material 171 is belled inward stretching or increasing the size of the hole 172 permitting the free passage of air into the vacuum box through the tube 103 and a simultaneous discharge of air from the vacuum box 99 through the enlarged hole 172 of the sheet of rubber material 171.

The trunnions 39 and 41 having their outer ends projected through enlarged holes 173 formed in the outer walls of the housings 59 and beyond those outer walls, the projected ends of the trunnions are formed with square end portions 39^b and 41^b. Edge sanding wheels 174, only one of which is shown in Figs. 2 and 5, are formed with con-

centric square holes into which the square end portions 39^b and 41^b of the trunnions 39 and 41 can be received for non-rotatively mounting the sanding wheels in position on those trunnions. Washers 175 having square holes are positioned on the square end portions 39^b and 41^b and against which the inner faces of the sanding wheels 174 are engaged. The sanding wheels 174 are removably retained in position by screws 176 received within recesses 177 formed in the outer faces of the sanding wheels 174 and threaded into complementary threaded holes formed in the outer ends of the square end portions 39^b and 41^b of the trunnions 39 and 41. Either one or both 15 of the sanding wheels 174 can be mounted on the square end portions 39^b and 41^b of the trunnions 39 and 41 and provide a convenient means for sanding the edge portions of the floor surface adjacent the side wall base boards which cannot be reached by the drum 28.

Located on the machine on one side of the vacuum box 99, there is an auxiliary drive to which the flexible shafts of small power operated tools can be attached to be driven from the motor 52. The auxiliary drive is characterized by a vertical shaft 178, see Figs. 3 and 6, which adjacent its bottom end is rotatively extended through a bearing bracket 179 secured to the inner face of the side wall 23 of the body 20. 25 Mounted on the vertical shaft 178, above and below the bracket 179, there are collars 180 which secure the shaft against any vertical movement while leaving it free to rotate. The top end of the vertical shaft 178 is rotatively extended through a bearing 181 secured to the inner face of the top wall 21 and then through a complementary hole formed in that top wall 21. Above the top wall 21, the top end of the vertical shaft 178 is formed with a square top portion 182 to 30 which the end of a flexible shaft, not shown, of a power operated hand tool, not shown, can be secured in any desired manner. Tools of a type which can be operated from the square top end portion 182 of the auxiliary drive might include 35 a grind stone for sharpening cutting tools, a buffer for polishing furniture, bar tops and the like, or any similar small tools.

The top face of the top wall 21 is formed with an upwardly extended shallow wall 183 which concentrically surrounds the top end of the vertical shaft 178 and which is internally threaded. A cap 184 is slipped into position over the top end of the shaft 178 and has its bottom end threaded into the wall 183 for enclosing the rotating top end of the shaft 178 when it is not being used. The top of the cap 184 is formed with external knurling 185 by which a grip can be had on the cap for turning it in one direction or the other.

The bottom end of the vertical shaft 178 is provided with a bevel gear 186 which in turn meshes with a complementary bevel gear 187. The bevel gear 187 is mounted on the inner end of a stud shaft 188 rotatively extended through the side wall 23 of the body 20. Means is provided for rotating the stud shaft 188 to in turn rotate the vertical shaft 178.

The hereinbefore referred to means for rotating the stud 113 and the means for rotating the stud shaft 188 are alike. Each of these means include bevel gears 189 mounted on the outer ends of the stud shafts 113 and 188. The bevel gears 189 are enclosed within housings 190 secured to the outer faces of the side walls 22 and 23 by means of screws 191. Within the housings

11

190, there are bevel gears 192, shown in dot and dash lines in Fig. 6, which mesh with the bevel gears 189. The bevel gears 192 having stud shafts 193 rotatively extended through the front walls of the housings 190 and secured to the rear ends of flexible shafts 194.

Within the housings 59, see Fig. 9, there are bevel gears 195 which mesh with the bevel gears 58 and which bevel gears 195 have stud shafts 196 rotatively extended through the rear walls 197 of the housings 59. The stud shafts 196 are connected to the front ends of the flexible shafts 194 to transmit rotations of the bevel gears 58 to the fan assembly 106 and the auxiliary drive shaft 178.

The use of the flexible shafts 63 and 194 permits free pivotal movement of the wall portion 46 about the pins 42 and 43 for releasing the drum 28 without any disconnection of the transmissions from the motor 56. It is thought that the operation of the machine will be clear from the foregoing description of the machine without the need to resorting to a detailed explanation of the operation.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of the side walls of the vacuum box, a throat extending from the fan and connected with the interior of said vacuum box through the said one side wall, a tube extended rearward from the dust pan and extended to the interior of said vacuum box through said front wall and substantially midway of the sides thereof, and a diaphragm assembly within the hollow body and spaced slightly from the other side wall of said vacuum box and including a throat portion connected with the interior of said vacuum box through the said other side wall, said diaphragm assembly comprising a housing having spaced end walls, said throat portion being integrally formed with the one end wall adjacent said vacuum box, a flange having a concentric opening positioned within said housing between said end walls, and a diaphragm within said housing in the space between said flange and said one end wall, said housing having holes connecting the space between said flange and the other end wall with the atmosphere, said diaphragm comprising a rubber ring within said housing in the space between said flange and the said one end wall, and a thin sheet of rubber material mounted across said rubber ring, said thin sheet of rubber material having a small hole concentric with said throat portion, and filter material stretched across said throat portion at its point of connection with the said other side wall.

2. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of the side walls of the vacuum box, a throat ex-

12

tending from the fan and connected with the interior of said vacuum box through the said one side wall, a tube extended rearward from the dust pan and extended to the interior of said vacuum box through said front wall and substantially midway of the sides thereof, and a diaphragm assembly within the hollow body and spaced slightly from the other side wall of said vacuum box and including a throat portion connected with the interior of said vacuum box through the said other side wall, said diaphragm assembly comprising a housing having spaced end walls, said throat portion being integrally formed with the one end wall adjacent said vacuum box, a flange having a concentric opening positioned within said housing between said end walls, and a diaphragm within said housing in the space between said flange and said one end wall, said housing having holes connecting the space between said flange and the other end wall with the atmosphere, said diaphragm comprising a rubber ring within said housing in the space between said flange and the said one end wall, and a thin sheet of rubber material mounted across said rubber ring, said thin sheet of rubber material having a small hole concentric with said throat portion.

3. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of the side walls of the vacuum box, a throat extending from the fan and connected with the interior of said vacuum box through the said one side wall, a tube extended rearward from the dust pan and extended to the interior of said vacuum box through said front wall and substantially midway of the sides thereof, and a diaphragm assembly within the hollow body and spaced slightly from the other side wall of said vacuum box and including a throat portion connected with the interior of said vacuum box through the said other side wall, said diaphragm assembly comprising a housing having spaced end walls, said throat portion being integrally formed with the one end wall adjacent said vacuum box, a flange having a concentric opening positioned within said housing between said end walls, and a diaphragm within said housing in the space between said flange and said one end wall, said housing having holes connecting the space between said flange and the other end wall with the atmosphere, said diaphragm comprising a rubber ring within said housing in the space between said flange and the said one end wall, and a thin sheet of rubber material mounted across said rubber ring, said thin sheet of rubber material having a small hole concentric with said throat portion, and filter material stretched across said throat portion at its point of connection with the said other side wall.

4. In a floor treating machine having an open bottomed hollow body enclosing a fan for blowing collected dust into a dust bag, a vacuum box mounted within the body and including a front wall and spaced side walls, the fan being mounted within the body adjacent one of the side walls of the vacuum box, a throat extending from the fan and connected with the interior of said vacuum box through the said one side wall, a

tube extended to the interior of said vacuum box through said front wall and substantially midway of the sides thereof forming an entrance port to said vacuum box, a diaphragm assembly within the hollow body and spaced slightly from the other side wall of said vacuum box and including a throat portion connected with the interior of said vacuum box through the said other side wall, a pipe extended upward from said vacuum box forming a second entrance port to said vacuum box, a cap closing the top end of said pipe and being removable so that a flexible hose can be connected with that top end for vacuum cleaning purposes, and a valve for closing said tube when said pipe is being used.

5. In a floor treating machine having an open bottomed hollow body enclosing a fan for blowing collected dust into a dust bag, a vacuum box mounted within the body and including a front wall and spaced side walls, the fan being mounted within the body adjacent one of the side walls of the vacuum box, a throat extending from the fan and connected with the interior of said vacuum box through the said one side wall, a tube extended to the interior of said vacuum box through said front wall and substantially midway of the sides thereof forming an entrance port to said vacuum box, a diaphragm assembly within the hollow body and spaced slightly from the other side wall of said vacuum box and including a throat portion connected with the interior of said vacuum box through the said other side wall, a pipe extended upward from said vacuum box forming a second entrance port to said vacuum box, a cap closing the top end of said pipe and being removable so that a flexible hose can be connected with that top end for vacuum cleaning purposes, and a valve for closing said tube when said pipe is being used, said valve comprising a valve housing formed in said tube intermediate of its ends and having an open top, a valve plate slidably positioned in said valve housing, and means for holding said valve plate in a raised or lowered position in said valve housing.

6. In a floor treating machine having an open bottomed hollow body enclosing a fan for blowing collected dust into a dust bag, a vacuum box mounted within the body and including a front wall and spaced side walls, the fan being mounted within the body adjacent one of the side walls of the vacuum box, a throat extending from the fan and connected with the interior of said vacuum box through the said one side wall, a tube extended to the interior of said vacuum box through said front wall and substantially midway of the sides thereof forming an entrance port to said vacuum box, a diaphragm assembly within the hollow body and spaced slightly from the other side wall of said vacuum box and including a throat portion connected with the interior of said vacuum box through the said other side wall, a pipe extended upward from said vacuum box forming a second entrance port to said vacuum box, a cap closing the top end of said pipe and being removable so that a flexible hose can be connected with that top end for vacuum cleaning purposes, and a valve for closing said tube when said pipe is being used, said valve comprising a valve housing formed in said tube intermediate of its ends and having an open top, a valve plate slidably positioned in said valve housing, and means for holding said valve plate in a raised or lowered position in said valve housing, said holding means comprising a tubular member mounted within the hollow body above said valve housing,

said valve plate having a portion projected from the open top of said valve housing, a flexible valve stem projected freely through said tubular member and having its bottom end secured to the projecting top portion of said valve plate, so constructed and arranged that said valve will be raised or lowered as said valve stem is raised or lowered relative to said tubular member.

7. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of the side walls of the vacuum box, a throat extending from the fan and connected with the interior of said vacuum box through the said one side wall, a tube extended rearward from the dust pan and extending to the interior of said vacuum box through said front wall and substantially midway of the sides thereof, a diaphragm assembly within the hollow body and spaced slightly from the other side wall of said vacuum box and including a throat portion connected with the interior of said vacuum box through the said other side wall, screening material extended across the entrance of the throat leading from said vacuum box to the fan permitting the free discharge of a dust-air mixture from said vacuum box to the fan, and a drawer in the bottom of said vacuum box for collecting larger articles which enter said vacuum box and which cannot pass through said screen material.

8. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of the side walls of the vacuum box, a throat extending from the fan and connected with the interior of said vacuum box through the said one side wall, a tube extended rearward from the dust pan and extended to the interior of said vacuum box through said front wall and substantially midway of the sides thereof, a diaphragm assembly within the hollow body and spaced slightly from the other side wall of said vacuum box and including a throat portion connected with the interior of said vacuum box through the said other side wall, screening material extended across the entrance of the throat leading from said vacuum box to the fan permitting the free discharge of a dust-air mixture from said vacuum box to the fan, and a drawer in the bottom of said vacuum box for collecting larger articles which enter said vacuum box and which cannot pass through said screen material, said vacuum box having an opening in the bottom of thereof through which said drawer can be removed to be emptied.

9. In a floor treating machine having an open bottomed hollow body enclosing a rotatively supported sanding drum behind which a dust pan is located for collecting dust thrown rearward by the drum and a fan for blowing collected dust into a dust bag, a vacuum box mounted within the body to the rear of the dust pan and including a front wall and spaced side walls, the fan being mounted within the body adjacent one of

the side walls of the vacuum box, a throat extending from the fan and connected with the interior of said vacuum box through the said one side wall, a tube extended rearward from the dust pan and extended to the interior of said vacuum box through said front wall and substantially midway of the sides thereof, a diaphragm assembly within the hollow body and spaced slightly from the other side wall of said vacuum box and including a throat portion connected with the interior of said vacuum box through the said other side wall, screening material extended across the entrance of the throat leading from said vacuum box to the fan permitting the free discharge of a dust-air mixture from said vacuum box to the fan, a drawer in the bottom of said vacuum box for collecting larger articles which enter said vacuum box and which cannot pass through said screen material, and filter material stretched across said throat portion leading to said diaphragm assembly so that air only will pass through said throat portion.
